2 SHEETS—SHEET 2.

UNITED STATES PATENT OFFICE.

JAMES WILLIAM TATUM, OF DURHAM, NORTH CAROLINA, ASSIGNOR TO SHAKER-DUMP COAL-GRATE CO., OF DURHAM, NORTH CAROLINA.

COAL-GRATE.

1,389,792.

Specification of Letters Patent. Patented Sept. 6, 1921.

Application filed February 17, 1921. Serial No. 445,649.

To all whom it may concern:

Be it known that I, JAMES W. TATUM, a citizen of the United States, residing at Durham, in the county of Durham and State of North Carolina, have invented certain new and useful Improvements in Coal-Grates; and I do declare the following to be a full, clear, and exact description of the invention, such as will enable others skilled in the art 10 to which it appertains to make and use the same.

This invention relates to an improved coal grate and one object of the invention is to provide a grate which may be formed in a plurality of sections connected in an improved manner and producing a grate which will be securely held in the set up position when in use.

Another object of the invention is to provide an improved construction of bottom grating and improved means for mounting this grating for horizontal swinging movement when shaking a fire, the grating being pivotally mounted and supported in an improved manner and further so mounted that while it may be easily removed and put in place when desired, it cannot readily become accidentally knocked out of place.

This invention is illustrated in the accompanying drawings, wherein:

Figure 1 is a view showing the improved grate in front elevation and placed within a fire place.

Fig. 2 is a vertical sectional view taken 35 along the line 2—2 of Fig. 1.

Fig. 3 is an enlarged vertical sectional view taken along the line 3—3 of Fig. 1.

Fig. 4 is a vertical sectional view taken along the line 4—4 of Fig. 3.

Fig. 5 is a transverse sectional view taken 40 along the line 5—5 of Fig. 3.

Fig. 6 is a perspective view of the bottom grating of the grate.

This improved grate is provided with a fire box having end walls 1 and 2, a front wall 3 and a rear wall 4. The end walls 1 and 2 are extended below the front and rear walls to provide supporting feet 5 and the end walls are provided with inwardly extending ledges 6 which taper rearwardly and provide supports for the bottom grating 7. This grating 7 rests upon the supporting ledges and is provided at its rear or inner end with a notch 8 to receive the pin extension 9 of the rear wall 4. This pin exten-

sion provides a fulcrum to pivotally mount the bottom grating thus permitting the bottom grating to be oscillated horizontally by means of the handle extension 10 at its forward end. This handle extension 10 will 60 be grasped by means of a suitable shaker (not shown) and ashes can thus be readily caused to pass through the slots of the grating. A lug 11 is provided to the rear of the handle extension 10 and the front wall 3 is 65 provided intermediate its length with a notch 12 so that the grating can be put in place beneath the front wall. When this grating is put in place, the lug passes through the notch 12 and by moving the 70 grating to one side, the lug can be moved out of direct alinement with the notch thus preventing any danger of the grating being accidentally moved forwardly out of the proper position. The end walls 1 and 2 are 75 provided at their forward ends with hooked arm extensions 13 for engaging the upper side portions of the front wall and the front wall is provided with arm extensions 14 for engaging the lower forward portions of the 80 end walls 1 and 2. Arm extensions 15 are provided at the upper rear end portions of the end walls to engage the rear wall, and arms 16 are carried by the rear wall for engaging the end walls 1 and 2. Fastener 85 bolts 17 pass through the arm extensions and through the walls so that these walls may be securely but releasably held in a set-up position. It should be noted that these walls are firmly held against any movement 90 when the bolts are in place and therefore the grate cannot become distorted.

The end wall is provided with rearwardly extending side flanges 20 for engaging the rear or inner wall of a fire place and further has its upper portion 4' inclined outwardly to overhang the fire box as shown clearly in Fig. 3. From an inspection of this figure, it will be seen that the rear wall together with its side flanges 20 and headplate 21 will provide a box-like structure when the grate is in place thus providing an air chamber in which air may accumulate and pass out through the openings 22 formed in the rear wall. The openings 22 formed in 105 the lower portion of this rear wall are provided in rows between the ribs 23 which taper upwardly and will serve to hold the coal in spaced relation to the rear wall. Therefore, air can pass into the fire-box 110

- through the openings 22 formed in the lower portion of the wall 4 and of course, may also pass into the fire-box through the usual openings 24 formed in the walls of the fire-box.
- 5 In addition, a portion of the air in the air chamber at the rear of the grate will pass out through the openings in the upper portion of the wall 4 and this air which discharges from the air chamber above the fire-box will
- 10 serve to drive the heat from the fire out into the room, the inclined upper portion 4' of the wall 4 serving as a deflecting surface.
- When this grate is to be used, it will be assembled as shown with the tongues 13 of the end walls engaging the outer face of the front wall and the tongues 14 engaging the outer faces of the end walls. The securing bolts for these tongues will be put in place and the end walls will then be connected
- 15 with the side flanges 20 of the rear wall by passing bolts through the slots of the tongues 15 and 16 carried by the end walls and rear wall. The bottom grating will be put in place and the grate is then ready to be installed. When the grate is placed in the fire-place 25, the flanges or walls 20 and the head-plate 21 will engage the inner wall 26 of the fire-place and thus provide the air chamber to receive the air which is to be fed
- 20 into the fire-box through the rear wall and which is to pass through the openings in the overhanging upper portion of this rear wall. The fire will be started and as this fire burns, the overhanging upper section of the rear wall will provide a deflector surface and the air passing through the openings in this overhanging upper portion of the wall will serve to drive the heat out into the room. The ribs 23 serve to prevent the coal
- 25 from accumulating in the rear portion of the fire-box against the rear wall and therefore there will be no danger of the openings in this rear wall becoming stopped up by ashes. When it is desired to shake the fire, it is simply necessary to grasp the handle extension
- 30 10 and oscillate the grate with the pin 9

serving as a fulcrum point. If it is desired to dump the grate, it is simply necessary to draw the grate outwardly through the space beneath the front wall and the contents of the fire-box may drop down upon the hearth. A grate for an open fire-place has thus been provided which can be easily and quickly put together or taken apart if necessary.

I claim:

1. A grate comprising a fire box having a rear wall, a forward wall and end walls, a depending fulcrum element carried by said rear wall, supporting means carried by said end walls, and a bottom grate extending beneath said forward wall and resting upon said supporting means and having its rear edge portion engaging said fulcrum to mount the grate for oscillating movement in a horizontal plane.

2. A grate comprising a fire box having end walls, a rear wall and a forward wall, supports extending inwardly from the end walls, a bottom grate extending beneath the forward wall and resting upon said supports, a fulcrum carried by the rear wall and engaging said grate to mount the same for oscillating movement, and a lug carried by said grate for passing through a cutout of the forward wall during insertion and removal of the grate.

3. A grate comprising a fire box having a rear wall, a forward wall and end walls, a depending fulcrum pin carried by said rear wall, supporting flanges carried by said end walls, a bottom grate extending beneath said forward wall and resting upon said flanges and at its rear provided with a pocket receiving said fulcrum pin to mount the grating for oscillating movement, a neck 85 extending from the forward edge of said grate beneath the forward wall, and a lug carried by the grate for passing through a recess in the forward wall.

In testimony whereof I have hereunto set my hand.

JAMES WILLIAM TATUM.
